MELTING FURNACE

Paul H. Romph, Detroit, Mich.

Application July 5, 1944, Serial No. 543,594

3 Claims. (Cl. 263—33)

1

The invention relates to melting furnaces of the type forming the subject matter of my former Patent 1,671,546 of May 29, 1928.

The instant invention is in the nature of an improvement in which certain defects in the former construction have been eliminated and other advantageous features have been secured. To this end the invention consists in the construction as hereinafter set forth.

In the drawings:

Fig. 1 is a side elevation of the furnace;

Fig. 2 is an end elevation thereof;

Fig. 3 is a plan view with top portion removed; and

Fig. 4 is an opposite end elevation.

The construction shown in my former patent consists essentially in a melting pot of substantially cylindrical form having conical end portions terminating in cylindrical spout portions of smaller diameter. This pot is arranged within an outer cylindrical casing with the spout portions extending through the end walls of said casing. The annular space between the pot and the outer casing forms a combustion chamber supplied with liquid or gaseous fuel in the lower portion thereof, while an aperture in the upper portion of the outer casing provides for escape of the products of combustion. The furnace is mounted on trunnions having their axis transverse to the axis of the cylinder and means is also provided for tilting the furnace on said trunnions for discharging molten metal out of one or the other of said spouts.

In the operation of a furnace of this construction it has been found that there is a tendency for the melting pot to crack. This is largely due to its shape which when heated and expanded concentrates stresses at certain points to initiate a fracture.

Another feature of the structure is a means for rotatively adjusting the pot so as to bring different portions of the cylindrical surface thereof to the bottom where the molten metal is held. However, as specially shown, such rotation of the pot carries with it the outer casing and it is, therefore, necessary to change the connections for feeding the fuel into said casing as these should always be located at the bottom.

With my improved construction I have eliminated the cause of fracture by changing the shape of the pot from a substantially cylindrical to a spherical form. I have also made provision for rotating the pot independently of any rotation of the outer casing which avoids the necessity of making any change in the fuel supply

connections. These and other changes have been incorporated in my improved construction which specifically is, as follows:

2

A is the pot which, as shown, is of substantially spherical shape but provided with cylindrical spout portions B on diametrically opposite sides thereof. The pot is preferably formed of cast metal having the spout portions B integral therewith. C is the outer casing which also is of substantially spherical shape but of a larger diameter than that of the pot. The casing is also formed of semi-spherical sections which are bolted or otherwise secured to each other at substantially the equator of the sphere. These sections fit about the spout portions of the pot and a refractory lining D covers the entire inner surface. To facilitate manufacture the semi-spherical sections are formed of a series of sheet metal segments C' welded to each other along meridian lines of the sphere. The lower section C' is also provided with a substantially rectangular enlargement E at its lower end connected to the spherical portion by inclined portions F. Trunnions G are attached to the lower section of the casing by means of plates G', the axis of said trunnions being transverse to the axis of the cylindrical spouts and in a slightly lower plane. The trunnions are journaled in bearings H at the upper ends of standards H' which latter rest upon the floor or other support. The fuel is supplied to the lower section of the casing by suitable conduits, portions I of which are mounted on the lower section C' of the casing to move therewith, while other portions I' are stationary. The connection between the stationary portion I' and the movable portions I is through a swivel coupling I' in alignment with the axis of one of the trunnions. The opposite trunnion has secured thereto outside of the supporting bearing H a worm wheel G' which is in mesh with a worm G'. This worm is mounted on a bracket H' at one side of the standard H on which bracket is also mounted a shaft G' connected to the worm through bevel gear wheels G'. A hand wheel G' on the shaft G' serves for manually rotating the same and through the gearing to rock a furnace upon its trunnions so as to discharge molten metal from one or the other of the spouts. When the furnace is in operation, the heat generated by the combustion of the fuel will be distributed around the entire spherical surface of the pot but, as the latter has the metal to be melted only in the lower portion, this will receive the highest heat from the fuel. However, due to the absorption of heat during the melting of the metal,

the latter will act more or less as a cooling agent. This will result in raising the actual temperature of the portion of the pot out of contact with the molten metal higher than that portion in contact therewith. Such condition is undesirable and I have, therefore, made provisions for rotating the pot about the axis of the cylindrical spouts to bring different portions of the spherical surface successively in contact with the metal. Such rotation is facilitated by mounting the cylindrical spout portions on rollers J which latter are journaled in brackets J' mounted on the section C². These rollers hold the spouts B out of frictional contact with the surrounding portions of the casing C but the clearance space is so small as to avoid passage of combustion gases therethrough. One of the spouts is further provided with a toothed wheel K at its outer end by means of which and a cooperating lever the pot may be partially rotated at frequent intervals. If desired, a gearing may be connected to the wheel K but this is not necessary as the lever operator is quite satisfactory. The upper section of the outer casing has an aperture C³ in the top thereof permitting the escape of the gaseous products of combustion and, if desired, an exhaust hood may be placed over this aperture to carry away such gases.

My improved construction has a much longer life than the construction forming the subject matter of my former patent and it is also more efficient. Thus, the outer casing being substantially parallel to the surface of the pot forms a uniform space therebetween for producing a substantially uniform heating effect over the greater portion of the area. However, immediately adjacent the burners the heat is more intense and this is directly conducted to the lower portion of the pot which is protected from overheating by the melting of the metal therein. At frequent intervals the pot is revolved step by step, each step bringing a portion previously out of the contact with the molten metal into contact therewith and, at the same time, removing a portion previously in contact with the molten metal to a position above the same. The result is that heat is conserved and, at the same time, the pot is held at a more nearly uniform temperature in all portions thereof which will increase its life.

It may be desirable in the melting of certain metals such, for instance, as the highly combustible magnesium, to close the spouts so as to maintain a non-oxidizing atmosphere within the pot. For this purpose cover plates L are provided to be detachably connected to the outer ends of the spouts by clamping bolts L'. Also, under certain conditions it is desirable to raise the atmospheric pressure within the pot, while under other conditions the pressure may be lowered to below that of atmosphere. This is provided for by attaching to one of said cover plates conduits, such as M, which are connected to either a source of higher pressure or of vacuum.

What I claim as my invention is:

1. A melting furnace comprising a substantially spherical melting pot having integral cylindrical spouts on diametrically opposite sides thereof, a substantially spherical outer casing surrounding and spaced from said pot and provided with openings for the passage of said spouts, said casing being formed of sheet metal segments joined to each other along meridian lines and provided with a refractory lining covering the inner surface, roller bearings mounted on said casing and engaging the outer portions

of said spouts to rotatively support said pot within said casing for independent rotation, means on one of said spouts facilitating independent rotation of the same, trunnions on opposite sides of said casing having a common axis transverse to the axis of said spouts, supporting bearings in which said trunnions are journaled, a conduit for supplying fuel to said combustion chamber having a portion thereof in axial alignment with one of said trunnions and having a swivel connection with a stationary conduit, and mechanism connected to the opposite trunnion for rotating the same to tilt the furnace so as to discharge molten metal through one or the other 15 of said spouts.

2. A melting furnace comprising a substantially spherical pot having cylindrical spouts integral therewith on diametrically opposite sides thereof, a substantially spherical outer casing surrounding said pot leaving a space therebetween for forming a combustion chamber, said casing being formed of sheet metal segments joined to each other along meridian lines, being also provided with a refractory lining covering 20 its inner surface and having openings through which said spouts extend, roller bearings mounted on said casing for engaging the outer portions of said spouts to rotatively support said pot within said casing for independent rotation, 25 detachable cover plates for closing the outer ends of said spouts, means connected to one of said cover plates for introducing a gas under a predetermined pressure other than that of the external atmosphere and maintaining said pressure on 30 the metal within said pot during the melting of the same, trunnions on opposite sides of said casing having a common axis transverse to the axis of said spouts, supporting bearings in which said trunnions are journaled, a conduit for supplying fuel to said combustion chamber having a portion in axial alignment with one of said trunnions and having a swivel connection with a stationary conduit, and means connected to the opposite trunnion for rotating the same to tilt 35 40 45 said furnace and to discharge the molten metal through one of the other of said spouts after removal of the cover plate therefrom.

3. A melting furnace comprising a substantially spherical melting pot having integral cylindrical spouts projecting from diametrically opposite sides thereof, a substantially spherical outer casing surrounding said pot leaving a space therebetween for forming a combustion chamber and provided with openings through which said 50 spouts extend, said casing being formed of sheet metal segments joined to each other along meridian lines and provided with a refractory lining covering the inner surface, roller bearings mounted on said casing and engaging the outer portions of said spouts to rotatively support said pot within said casing for independent rotation, cover plates for closing the outer ends of said spouts, means connected to one of said cover plates for introducing a gas under a predetermined pressure other than that of the external atmosphere and maintaining said pressure on the metal within said pot during the melting of the same, a conduit connecting with one of said cover plates for the introduction or withdrawal of gas to raise or lower the pressure within said pot, trunnions on diametrically opposite sides of said casing having a common axis which is transverse to the axis of said spouts, supporting bearings in which said trunnions are 55 60 65 70 75 journaled, a conduit for supplying fuel to said

combustion chamber having a portion extending in axial alignment with one of said trunnions and having a swivel connection with a stationary conduit, means connected with the other of said trunnions for rotating the same to tilt said furnace and pot so as to discharge molten metal through one or the other of said spouts, and means for turning one of said spouts to rotate said pot within said casing.
